UNITED STATES PATENT OFFICE.

HIRAM H. HATCH, OF CLEVELAND, OHIO.

VENTILATING-STOP FOR WINDOW-SASHES.

1,264,181.

Specification of Letters Patent. Patented Apr. 30, 1918.

Application filed May 11, 1915. Serial No. 27,459.

To all whom it may concern:

Be it known that I, HIRAM H. HATCH, a citizen of the United States of America, residing at 2211 East 80th street, Cleveland, in the county of Cuyahoga and State of Ohio, have invented certain new and useful Improvements in Ventilating-Stops for Window-Sashes, of which the following is a specification.

10 My invention relates to improvements in ventilating stops for window sashes, and has for its object the provision of a cheap, simple and efficient stop device which may be readily attached to window sashes without interfering with their movement past each other in any way, nor necessarily entail the mortising of the window sash in attaching the device thereto. My improved device is adapted to be attached substantially flush 15 with the side bar of an upper window sash, in any desired position; and normally all the members thereof lie in substantially the same plane, so that the window sashes are free to slide past each other without interference. Upon adjusting the device, however, a stop is formed from the movable members which will resist any ordinary attempt to force the window sashes past each other.

20 Preferably, the device of my invention is stamped from sheet metal, and comprises a base plate whereon two hinged movable members, adapted to form the stop, are pivotally mounted and normally lie in the common plane of the base plate. These movable members, however, are adapted to be moved into angular relation with said base plate, and suitably adjusted or retained in position, as by the insertion of a pin, whereby a rigid 25 stop is formed, which will prevent the opening of the window sashes beyond their ventilating position.

30 In devices of this general character which have been manufactured to my knowledge prior to my invention, there has frequently arisen the necessity for mortising the window sashes in order to receive a detent member, which member commonly is provided with a spring or other auxiliary attachment 35 for maintaining the detent member in its locking relation. Other devices have involved the employment of somewhat cumbersome and movable parts which are found to be more or less in the way, and all of these 40 devices are more likely to become out of order than is my simplified fastener herein.

explained. The features thereof may be best set forth in connection with the accompanying drawings wherein:—

Figure 1 is a perspective fragmentary view of two window sashes in ventilating position with my improved ventilating stop suitably secured in position for use.

Fig. 2 is an enlarged plan view of one of the devices of my invention, and

Fig. 3 is a view in side elevation showing the same device with a window sash in engagement with the stop member, respectively indicated by dotted lines.

Fig. 4 is a plan view of a modification.

Fig. 5 illustrates a lighter construction embodying my invention, whereby a plurality of ventilating positions are provided for.

Throughout the several figures of the drawings, I have employed the same character of reference to indicate similar parts.

Referring first to Fig. 1, it will be seen that the window sashes *a*, *b* are mounted to slide vertically in the usual manner. Sufficient clearance normally exists for attaching my improved device to the side bar of the upper sash without interfering with the movement of the lower sash, so long as the members of said device are in the common plane of the base plate.

Accordingly, I have shown in Fig. 1, one of my devices attached at the proper distance upon the left of the upper sash, which device I have shown in its blocking or ventilating relation. Two or more of these devices, may be applied to the upper sash, as upon the right and left hand sides thereof, should greater security be desired, or in the event that the window sashes are of unusual width, although one of said devices normally is adequate for each pair of window sashes.

In order better to explain the structure involved I may now refer to the type of my improved device, which is shown in Figs. 2 and 3, although the structural features do not materially vary in the different embodiments herein illustrated. The base plate *c* is provided with two pivoted members *d*, *e*, which are adapted normally to lie in the plane of the base plate. These members are permanently pivoted to the base plate by means of an upper pin *f*, while a removable pin *g* normally retains the members *d*, *e* in their inoperative position, as shown in Fig. 2. The base plate, however, is provided with a median elevated rib or corrugation *c*²

through which the pin *g* is adapted to be inserted in order to secure the lower end of member *e* thereto, approximately in horizontal relation, while the member *d*, which is 5 permanently pivoted thereto, extends at an acute angle with the base plate as shown in Fig. 3, by dotted lines, so that the members of my improved device assume substantially the relation of a figure "4." In this position, 10 it is obvious that the lower sash cannot be moved past the horizontal plane assumed by member *e*, as shown in Figs. 1 and 3. Moreover, the device may be affixed at any desired 15 position along the window sash and is positively locked in its extended relation by the pin *g*, so that it may not be manipulated to open the window from without.

With the relatively heavy device of Fig. 3, 20 the lower sash may be planed to form a shallow slot for permitting the movement of the sashes past each other, if only a slight clearance is afforded between the window sashes. With the lighter construction, however, the 25 parts lie substantially in so nearly the same plane that the usual clearance is sufficient to permit my improved device to be attached at one or both sides of the upper sash, without impeding the usual movement of the sashes past each other.

30 In Fig. 5, the several parts are shown of the type already described, except that duplicate members *d*, *e*, are provided upon the base plate in order to afford two different ventilating positions for the window sash, as 35 may be desirable under varying circumstances, and without altering the position of the base plate upon the upper sash. Thus, either the upper or the lower set of movable members may be actuated into the blocking 40 position as already described, in order to permit a wider or narrower ventilating space at the bottom or top of the window opening.

This structure also shows a slight modification, (better illustrated in Fig. 4) wherein in the member *e* instead of requiring a cross-pin for holding it in position, is provided with lateral extensions *e*¹, which are adapted to enter the laterally slotted ribs *c*² provided 45 in the base plate, in order to adjust the device in its locking or unlocking position. When the window sash is raised, of course, it will pass both sets of members provided they lie substantially in the plane of the 50 base plate, but if one set of pivoted members is adjusted as shown in the upper portion, Fig. 5, of the drawing, the lugs will react against the corrugated base plate to resist the slight outward strain imparted thereto, 55 and the upper member *d* will effectually

prevent the further movement of the window sash. All of these devices have the distinct advantage of being practically invisible from the exterior of the window opening, and they may not be tampered with under 65 ordinary circumstances.

In the consideration of the foregoing, it will be perceived that my improved device is of the simplest possible construction, and therefore is neither likely to get out of order 70 nor become broken in use. No springs are required, and the only detachable member is a pin which may easily be replaced should it be misplaced. The prime structural feature inherent in my device is that the parts lie 75 approximately in a common plane, so that their maximum thickness is essentially that of the corrugated or ribbed base plate *c*, *c*², which may be inserted or attached to one of the window sashes without obstructing the 80 movement of the other. When the movable parts are adjusted to their locking position, it is seen that the one stays the other, so that my device is stronger than is obtainable with members of the same size and weight, 85 which do not stay each other.

Having now explained the embodiment of my invention I claim as new, and desire to secure by Letters Patent, the following:

1. In a ventilating stop device, the combination with a centrally recessed and corrugated base plate formed of sheet metal, a second member pivoted from its upper end, adapted normally to lie within said recess and an additional member pivoted to the 95 latter, and locking means adapted positively to secure the additional member in an intermediate corrugation of the base plate, whereby said pivoted members may be caused to form substantially a figure "4" with the 100 base plate when in locking position, substantially as set forth.

2. In a window stop device, the combination with a centrally recessed base plate transversely ribbed along its rear face, of a member pivoted from its upper end in an upper rib of the base plate, an additional member pivoted to the first named member and adapted to lie flush with it in the recess of the base plate, and a locking part adapted 105 to be inserted in a lower rib of the base plate and temporarily and positively lock the members in extended position, substantially as set forth.

In testimony whereof I hereunto affix my 115 signature in the presence of two witnesses.

HIRAM H. HATCH. [L. s.]
